UNITED STATES PATENT OFFICE.

EDWARD E. KELLEY, OF WEST FALMOUTH, MASSACHUSETTS.

DESIGN FOR AN ICE-CREAM-CONE HOLDER.

50,276.

Specification for Design.

Patented Feb. 6, 1917.

Application filed February 16, 1916. Serial No. 78,773. Term of patent 7 years.

To all whom it may concern:

Be it known that I, EDWARD E. KELLEY, a citizen of the United States, residing at West Falmouth, in the county of Barnstable and State of Massachusetts, have invented an original and ornamental Design for Ice-Cream-Cone Holders, of which the following is a specification, reference being had to the accompanying drawings, forming part hereof.

The figure is an elevation of an ice cream cone holder illustrating my new design.

I claim the ornamental design for an ice cream cone holder as shown.

EDWARD E. KELLEY.
